UNITED STATES PATENT OFFICE.

GEORGE W. HAHN, OF PITTSBURG, PENNSYLVANIA, ASSIGNOR TO THE H. J. HEINZ COMPANY, OF SAME PLACE.

DESIGN FOR A BOTTLE-CAP.

SPECIFICATION forming part of Design No. 19,835, dated May 13, 1890.

Application filed April 7, 1890. Serial No. 346,972. Term of patent 7 years.

To all whom it may concern:

Be it known that I, GEORGE W. HAHN, of Pittsburgh, in the county of Allegheny and State of Pennsylvania, have invented a new 5 Design for Bottle-Caps, of which the following is a full, clear, and exact description.

My invention relates to a design for bottle-caps; and it consists in the design as herein-after described, and particularly stated in the 10 following claim.

In the accompanying drawings, Figure 1 is a side elevation of a bottle-cap embodying my design. Fig. 2 is a top plan view thereof. Fig. 3 is a vertical section on the line III III 15 of Fig. 1. Fig. 4 is a horizontal section on the line IV IV of Fig. 1.

Like symbols of reference indicate like parts in each.

In the drawings, 2 represents the bottle-cap, which is formed with a series of prominent 20 longitudinal corrugations or ribs 3 and with an externally-projecting spiral rib or bead 4, which forms an essential feature of the design. At the top is a portion 5 of smaller diameter than the lower part of the cap. 25

I claim—

The design for bottle-caps, substantially as herein described and shown.

In testimony whereof I have hereunto set my hand this 3d day of April, A. D. 1890.

G. W. HAHN.
